RATION OF ONTARIO, CANADA.

QUADRUPPLICATING-BOOK.

1,087,091.

Specification of Letters Patent. Patented Feb. 10, 1914.

Application filed April 21, 1913. Serial No. 762,535.

To all whom it may concern:

Be it known that we, CLARENCE L. JOHN-
STON and CHARLES L. BLUETT, both citizens
of the United States, residing at Oakland,
5 in the county of Alameda and State of Cali-
fornia, have invented new and useful Im-
provements in Quadruplicating-Books, of
which the following is a specification.

This invention relates to quadruplicating
10 sales books.

The invention consists of the parts and
the construction and combination of parts
as hereinafter more fully described and
claimed, having reference to the accompany-
15 ing drawings, in which—

Figure 1 is a perspective view of the de-
vice in folded position. Fig. 2 is a perspec-
tive view of the device in unfolded position.
Fig. 3 is a perspective view of the device
20 folded for use. Fig. 4 is a detail view show-
ing the stubs. Fig. 5 is a perspective view
of one of the detachable leaves. Fig. 6 is a
diagrammatic view showing the manner of
folding the leaves for use.

25 In carrying out the invention we build up
a book comprising two stacks of leaves
A—B; the stack A being of transparent ma-
terial commonly known as tissue, and num-
bered consecutively beginning at 1 at the
30 bottom of the stack; the highest number
being at the top of the stack. This tissue
stack A is bound to one end of a back 2,
which latter is approximately twice the
length of the stack A; the back 2 being of
35 sufficient length to be folded over and over-
lie all but the stub 3 of the tissue stack A.
The stack B is bound in a stub 4, to the top
of the overlying portion of the back 2, so
that ordinarily the two stacks will lie one
40 on top of the other; the tissue stack being
on top. The stack B is provided with a
flexible stop card 5.

The stack B consists of leaves, each di-
45 vided crosswise by lines of perforations 6,
into three substantially equal sections 7—8
and 9; each section being of approximately
the size of one of the tissue leaves of the
stack A. A double-faced carbon 10 of ap-
proximately the size of section 7 is bound

to the top of the stub 4 of the stack B. The 50
middle section 8 is carbonized on its top face
and imprinted on its under face as the leaf
is viewed when opened out; and the upper
and lower sections 7—9 are similarly im-
printed on their top face, although not car- 55
bonized. When the book is made up the sec-
tions 9—8—7 are over-folded on one an-
other, so as to reduce the bulk of the book.

In practice when it is desired to make a
quadruplicate record, the stack B is lifted 60
so as to allow the tissue stack A to be thrown
backward away from the stub. Next, the
top leaf of stack B is lifted to allow the
stop card 5 to be slid underneath and the
leaf opened out. Next, the double-faced 65
carbon 10 is over-laid on the top section
7. A tissue sheet is then laid on the top of
the double-faced carbon. Next the section
9 is folded over on the carbon face of the
70 section 8 and then the two last folded sec-
tions are folded over on said transparent
sheet, which over-lies the double-faced car-
bon. By writing then on the imprinted ex-
posed surface of the middle section 8, a
75 quadruplicate record is made.

The leaf containing the three sections
7—8—9 may then be torn out of the book
leaving the tissue record in the book; the
tissue record being then turned under the
entire stack B, leaving a fresh tissue sheet 80
exposed ready for the next operation.

Having thus described our invention, what
we claim and desire to secure by Letters
Patent is—

A quadruplicate book consisting of a 85
stack of leaves, each divided crosswise into
three substantially equal sections, a stack of
tissue leaves of approximately the size of
one of said sections, a flexible back by which
the two stacks are connected so that one 90
stack may overlie the other, a double-faced
carbon of approximately the same size as
one of said sections, and bound into the stub
of said sectional stack, the said sectional
stack having a middle section carbonized on 95
its top face as the leaf is viewed when
opened out, said double-faced carbon fold-
able over the top section of said sheet, and

one of said tissue sheets foldable over the double-faced carbon, the lower section of said sectional sheet foldable over the carbon face of the middle section, and two last folded sections foldable over said tissue sheet which over-lies the double-faced carbon.

In testimony whereof we have hereunto

set our hands in the presence of two subscribing witnesses.

CLARENCE L. JOHNSTON.
CHARLES L. BLUETT.
